UNITED STATES PATENT OFFICE.

WILLIAM KOURIM, OF WILLOUGHBY, OHIO, ASSIGNOR TO WILLOUGHBY SAUSAGE COMPANY, OF WILLOUGHBY, OHIO.

FLAT WIENER.

Application filed July 27, 1927. Serial No. 208,845.

The enormous demand for sandwiches of the so-called "hot dog" type that are consumed in large numbers by the public has created a need for a wiener sausage that is 5 peculiarly adapted for use in sandwich making. The shape of the rolls commonly availed of as the outside layer parts or sections, of a sandwich, together with the problem of cooking the wiener have developed certain requirements that a sausage designed to meet 10 this need must satisfactorily fulfill. Such a sausage must be formed so as to be readily cooked, either by broiling, frying or boiling, and also must be of a shape enabling it to be 15 easily confined between the layer parts of a sandwich.

In meeting the objectives stated this invention provides a wiener or sausage of substantially flat form which may be made in a chain 20 or string as is the usual custom.

With these and further objects in view, as will in part become apparent and in part be hereinafter stated, this invention comprises certain novel constructions, combinations and 25 arrangements of parts to be subsequently specified and claimed. For a complete understanding of the invention reference may be had to the following description and accompanying drawings, in which:

30 Figure 1 is a perspective view of a string of wieners made in accordance with the invention.

Figure 2 is a fragmentary plan view of the apparatus, with certain parts broken away, 35 somewhat enlarged to more clearly show the particular construction.

Figure 3 is an end elevation showing in detail the hinge and clasp construction of the wire members.

40 Figure 4 is a perspective view of the wire members comprising the hinge and clasp structure taken alone.

Figure 5 is a perspective of a unit of the apparatus showing in detail the construction 45 of the partitions and bottom thereof.

While the preferred form of the invention is hereinafter set forth, it is to be understood that it is not to be limited to the exact construction set forth, because various modifications of the details may be made in putting 50 the invention into practice within the purview of the appended claims.

A chain or string of flat wieners made in accordance with my invention is shown in 55 Fig. 1 and designated by the reference char-

acter 1. This chain or string comprises wieners 2 that are connected together by link members 3, as is the usual custom. Attention is called to the substantially rectangular cross section of the wieners or sausage that provides 60 the long flat shape so desirable in sandwich making. These wieners may be readily cooked in any suitable manner as their rectangular formation permits them to lie flat on any cooking surface which may be availed 65 of, in frying or broiling them. Obviously they may be boiled or roasted if this manner of cooking is found to be desirable. It is to be clearly understood that the use of these wieners, as made along the lines of my invention 70 is not to be limited to sandwich making as their ability of being easily cooked in various manners adapts them to use of the most general character.

I have found it to be advantageous to make 75 the apparatus employed in the manufacture of the flat weiners in sections or units, one of which is shown in Fig. 5 and designated by the reference character 4. These units are adapted to be hung in any suitable curing 80 place, as a smoke house, by a handle 5, located on one end thereof. This handle is made of stiff wire for reasons previously set forth, although any material desired could be used 85 in its construction.

The units are preferably made entirely of wire mesh or screen, together with stiff wire, so as to afford an exposure of the entire surface of the wieners to the smoke, thereby insuring the complete curing thereof.

The unit 4 comprises a top and bottom, 90 6 and 7, which are made from wire mesh material, as previously described. Secured to the top and bottom in any suitable manner, such as by soldering, are the wire members 8. 95 These members 8 are so designed that one end thereof acts as hinge members, while the other end is bent to provide the clasp structure that detachably holds the top and bottom together. The wire members 8 consist 100 of a piece of relatively stiff wire that is bent in substantially a U-shape. The free ends thereof are bent over to provide the hinge portions 9, having openings 10 therein. A bend 11 of the U-shape wire member is offset 105 from the remainder thereof by the portions 12 to provide the clasp structure. It is notable that the portions 12 are inclined slightly back on the wire to afford the necessary spring gripping or clasping action. In order 110

to allow for the thickness of the apparatus the members 8 that are secured to the bottom 7 have their hinge portions 9 offset from the remainder of the wire and are connected thereto by the portions 13.

A hinge member or rod 14, having headed ends 15, passes through the openings 10 in the wire members 8, thereby hingedly connecting the top and bottom, the headed ends 10 prevent the rod from sliding through the openings.

So as to accommodate the links that connect the wieners or sausages I have designed a particularly novel construction of the partitions forming the sides of the forms. Running transversely across the bottom 7, on the side opposite the wire members are the partitions 16. These members are of the same wire mesh material used throughout the remainder of the construction and are secured to the bottom in any manner found advantageous, such as soldering. I have found that the same solder that fastens the wire members to the bottom may be availed of to also fasten the partitions 16 thereto. As clearly shown in Figure 5 the alternate ends of the portions are shortened, as shown at 17, to accommodate the links. It will be seen that the partitions 16, together with the bottom 7, cooperate to make up the forms in which the sausages are compressed, said forms being denoted by reference character 18.

In utilizing this apparatus for the manufacture of flat wieners, as described above, the raw or uncured wieners are placed in the forms in the bottom, the top is then closed and held in the closed position by the clasp structure. This presses the wieners out into the flat or rectangular formation due to the shape of the forms in the unit. This unit is then hung in a smoke house or similar curing plant where it remains for the necessary length of time. While in the smoke house the meat will have been cured and the wiener

will retain its rectangular formation after 45 it has been removed from the form, due to the curing thereof in this shape. It will be noted that this apparatus provides for the very speedy manufacture of sausages, as they may be run directly from the filler into this 50 apparatus without wasting any time or employing any more steps.

The apparatus previously described may be availed of in the curing of sausages of any shape, as the foraminous or mesh structure 55 of the forms or compartments thereof permits of the exposure of the entire surface of the meat to the curing element. This apparatus will accommodate a string of sausages as they come from the filling machine, thereby obviating any need for additional steps in the process of sausage manufacture, if this apparatus is employed.

The method of curing sausages hereinbefore set forth is intended to be an important 65 part of this invention as the various steps of this method are susceptible of slight changes without in any way departing from the spirit of the invention.

Having thus described my invention what 70 I claim as new, and desire to secure by Letters Patent of the United States, is:—

1. As a new article of manufacture a wiener having opposed substantially parallel flat sides adapting it for sandwiching purposes. 75

2. As a new article of manufacture a wiener having a plurality of flat sides, each of substantial surface area.

3. The method of manufacturing wiener sausage which comprises the formation of a 80 sausage, compressing said sausage while in the raw state to produce a flat sided sausage, and curing said sausage while compressed to cause the flattened shape to be retained after curing.

In testimony whereof I affix my signature.

WILLIAM KOURIM.
